DESIGN FOR A COMBINATION KNIFE SHARPENER AND CAN OPENER

Rudolph Boettinger, Englewood, N. J.

Application December 20, 1944, Serial No. 117,008

Term of patent 14 years

(Cl. D22—2)

To all whom it may concern:

Be it known that I, Rudolph Boettinger, a citizen of the United States, residing at Englewood, in the county of Bergen and State of New Jersey, have invented a new, original, and ornamental Design for a Combination Knife Sharpener and Can Opener, of which the following is a specification, reference being had to the drawing, forming a part thereof.

In the drawing:

Fig. 1 is a front elevational view of a combination knife sharpener and can opener showing my new design.

Fig. 2 is a side elevational view.

Fig. 3 is a back elevational view.

Fig. 4 is a bottom plan view.

I claim:

The ornamental design for a combination knife sharpener and can opener, substantially as shown.

RUDOLPH BOETTINGER.
